UNITED STATES PATENT OFFICE.

ANTHONY A. MULAC, OF ALLIANCE, OHIO, ASSIGNOR TO THE BUCKEYE TWIST DRILL COMPANY, A CORPORATION OF OHIO.

EXPANSION REAMER.

Application filed May 27, 1921. Serial No. 473,014.

To all whom it may concern:

Be it known that I, ANTHONY A. MULAC, a citizen of the United States, residing at Alliance, in the county of Stark and State of Ohio, have invented new and useful Improvements in Expansion Reamers, of which the following is a specification.

The invention relates to reamers for cutting pump and engine cylinders and the like, and the object of the improvement is to form the body of the reamer from an integral cylindric block which may be expanded uniformly at all points in its periphery.

The invention is illustrated in the accompanying drawings, forming part hereof, in which—

Figure 1 is a side elevation of the improved reamer, secured on a stem;

Fig. 2, a detached end view of the reamer; and

Fig. 3, a longitudinal section of the reamer as on line III—III, Fig. 2, showing the stem and blades in side elevation.

Similar numerals refer to similar parts throughout the drawings.

The body 1 is made of a cylindric block of resilient metal, which may be chrome or nickel steel. A series of longitudinal grooves is provided in its periphery, in which a series of blades 3 are secured as by screws 4, and a longitudinal channel 5 is preferably provided in front of each blade, for receiving the cuttings in the usual manner.

A tapered or conical axial bore 6 is provided in the body for receiving the tapered or conical shank 7 of the stem 8 of the reamer, at each end of which shank the stem is threaded to receive nuts 9 and 9' by which the body of the reamer may be adjusted endwise upon the shank.

An outer series of longitudinal bores 10 is provided in the body, adjacent to the periphery thereof, and an inner series of longitudinal bores 11 is provided in the body adjacent to the axial bore; one bore of each series being preferably located in each section of the body between the successive blades, and the outer and inner bores alternating with each other; as shown in Fig. 2 of the drawings.

A series of longitudinal kerfs 12 is cut in

the body, extending outward from the axial bore to the longitudinal bores 10 of the outer series; and a series of longitudinal kerfs 13 is cut in the body extending inward from the periphery to the longitudinal bores 11 of the inner series, the inner and outer kerfs alternating with each other, and it is evident that the body of the reamer may be expanded by an endwise adjustment of the tapered shank in the axial bore thereof.

A flexing of the body around the bores at the one side of the kerfs is permitted by an opening of the other side of the kerfs, when the tapered shank of the stem is adjusted in one direction, and the resilience of the metal in the body will contract it when the shank is adjusted in the other direction.

The longitudinal bores at the bottom of the kerfs are not essential, but they are preferred to prevent a fracture of the body when the same is expanded; and it is evident that the expansion and contraction of the body will be uniform end to end and throughout its periphery. This result follows from the accordion like action of expansion and contraction given by the alternate arrangement of the kerfs.

I claim:—

1. A reamer including a cylindric body having an axial bore, a series of kerfs extending outward from the axial bore part way to the periphery and a series of kerfs extending inward from the periphery part way to the axial bore, the kerfs of one series alternating with the kerfs of the other series, and means for expanding the body by an opening of the kerfs.

2. A reamer including a cylindric body having a tapered axial bore, a series of kerfs extending outward from the axial bore part way to the periphery and a series of kerfs extending inward from the periphery part way to the axial bore, the kerfs of one series alternating with the kerfs of the other series, and a tapered shank adjustable endwise in the axial bore.

3. A reamer including a cylindric body having an axial bore, an outer series of longitudinal bores adjacent to the periphery and an inner series of longitudinal bores adjacent to the axial bore, alternating with

the bores of the outer series, a series of kerfs extending from the axial bore to the bores of the outer series, and a series of kerfs extending from the periphery to the bores 5 of the inner series, and means for expanding the body by a flexion thereof around the longitudinal bores.

4. A reamer including an integral cylindrical body having an axial bore, the body being formed in an annular accordion like 10 shape to permit a uniform expansion throughout.

ANTHONY A. MULAC.
